(57) **CLAIM**

The ornamental design for a stackable compact disk case, as shown and described.

DESCRIPTION

FIG. 1 is a top perspective view of a stackable compact disk case showing our new design;

FIG. 2 is a top plan view of our new design;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a bottom plan view thereof.

The broken lines showing of a disk and other elements are for illustrative purpose only and forms no part of the claimed design.
